UNITED STATES PATENT OFFICE.

GEORGE H. FORSYTH, OF CHICAGO, ILLINOIS.

DISK WHEEL.

1,378,537.

Specification of Letters Patent. Patented May 17, 1921.

Original application filed November 26, 1918, Serial No. 264,253. Divided and this application filed February 21, 1921. Serial No. 446,860.

To all whom it may concern:

Be it known that I, GEORGE H. FORSYTH, a citizen of the United States, residing at Chicago, in the county of Cook and State 5 of Illinois, have invented certain new and useful Improvements in Disk Wheels, of which the following is a specification.

This application is a division of my co-pending application Serial No. 264,253.

10 The invention of this application relates to metal wheels and more particularly to that type characterized by the employment of a disk body portion having fixedly associated therewith an overhanging felly portion adapted to receive a demountable rim.

15 The principal objects of the invention are the provision of rim-assembling means which shall efficiently support the forward edge of the rim, transmitting the radial 20 shocks of impact in use directly to the disk body portion of the wheel, and which shall furthermore impart to a wheel of this type an appearance of peripheral stability by increasing the apparent thickness of the felly 25 in simulation of the felly of a wood wheel of artillery type.

30 In order that the invention may be readily understood and appreciated by those skilled in the art, I have in the accompanying drawings and in the following description predicated thereon, set forth the invention as embodied in wheel structures differing in detail.

In the drawings—

35 Figures 1 and 2 are views in vertical section illustrating the invention as embodied in double disk wheels in the front face only, Fig. 1 corresponding to Fig. 8 of the parent application, and Fig. 2 being a composite of Figs. 11 and 13 of that application;

40 Figs. 3, 4 and 5 are fragmentary sectional views illustrating the invention as applied to wheels having a varying felly structure, both front and rear, and corresponding respectively to Figs. 14, 15 and 16 of the parent 45 application; and

Figs. 6 and 7 are fragmentary views illustrating the invention as applied in the front face only of double and single disk wheels respectively.

50 Having reference to Figs. 1 and 2, these wheels are represented as comprising the hub 11 with the forward hub plate 12 and a rear hub plate 13 developed into the usual brake drum 14. Filler member 15 is employed within the space between the two

hub plates usually occupied by the spokes of a wooden wheel. The body of the wheel proper comprises the front and rear disks 16 and 17 having their central portions separated by the filler member 15 and 60 clamped between said filler member 15 and the two hub plates 12 and 13 by the bolts 18.

In Fig. 1 the front disk 16 is bent rearwardly at 19 from a step, shoulder or bead at 20. From 19 the disk extends radially 65 and then rearwardly to form a felly portion having a vertical front face 21 and a horizontal rim-receiving face 22. The rear disk 17 extends in a radial direction and then rearwardly parallel and in juxtaposition to 70 the portions 21 and 22 of the disk 19, and at its margin is housed within the lipped over margin 23 of the disk 16.

The overhanging felly portion of the wheel is adapted to receive the demountable 75 rim 24, which is preferably of slightly less inner diameter than the outer diameter of the felly portion 22 whereby as the rim is assembled laterally with the felly the latter will be subjected to inwardly directed radial 80 compression shared by the disk body of the wheel.

As rim-assembling means a shim or shims are employed comprising either an annular shim, split or integral, or a plurality of individual shims disposed at spaced intervals about the wheel. The shim or shims preferably comprise a body portion 25, heel portion 26 and a head portion 27, the body portion 90 of the shim and the vertical disk portion 21 being apertured to accommodate the assembling bolts 28. The heel 26 of the shim serves as a fulcrum, being seated upon the ledge 19 above the bead or step 20. As the bolts 28 are drawn home, the shim is 95 tilted upon its fulcrum 26 causing its head 27 to describe an arc about the fulcrumal point which exerts a force rearwardly and outwardly upon the forward edge of the rim. This results in forcing the rim rearwardly 100 to compress the felly portion 22, and also transmits radial pressure inwardly upon the disk body 16. The assembled wheel presents a front face wherein the body portion 25 of the shim is substantially flush with the 105 outer portion of the disk 16 relieved by the bead 20. Where an annular shim is employed, as is preferable, the front face of the shim presents the appearance of a felly face conveying an impression of felly-thickness 110

similar to that of the wooden felly on a wheel of the artillery type.

The description of Fig. 1 applies in substance to Fig. 2, the principal difference being that the horizontal wall 19 extends rearwardly to substantially the median plane of the wheel where the vertical portions of the two disks extend radially side by side and then in opposite directions front 10 and rear to form a felly substantially T-shaped in cross section, overhanging front and rear instead of at the rear alone. The upper part of Fig. 2 includes the mounting of the valve stem as illustrated in Fig. 3 of 15 the parent application, whereas the lower portion of the figure is directed to the wheel generally as shown in Fig. 11 of the parent application. Aside from these points of difference, and the fact that beyond the bead 20 the wall 19 is offset as illustrated at 19^a, the structure pertinent to this invention is the same, and the appearance presented by the shim 25 corresponds to that of Fig. 1.

In Figs. 3 and 4 the forward and rear 25 disks 29 and 30 are bent toward each other to form the steps or beads 31, 32 whence to extend horizontally at 33, 34 and thence radially at 35, 36 in contact with each other and thence horizontally in opposite directions 37, 38 to form a T-shaped felly to support the rim 39. Upon the two sides of the wheel both front and rear are mounted annular shims 40-41 having their heel portions fulcrumed upon the beads 31, 32 and 30 assembled with the wheel by means of the long bolts 42 extending between both of the shims and through the walls 35, 36. In this 35 particular form of construction the disks 29 and 30 are placed under radial stress by 40 the inward thrust applied to the beads 31, 32 as the shims are drawn together with their heads beneath the demountable rim.

In Fig. 4 the demountable rim is omitted, the tire setting directly upon the felly 45 portions 37, 38 and being confined laterally by means of the head portions 35^a and 36^a of the shims. In this instance the particular function of the shims is to retain the tire and to impart an appearance of felly 50 thickness without regard to any material stress imparted to the disks.

A construction somewhat similar to Fig. 4 is shown in Fig. 5, the demountable rim being omitted and the tire held in place by 55 the heads of the shims. Slight differences are also present in the configuration of the felly portion of the disks.

In Fig. 6, corresponding to Fig. 9 of the parent application, the invention is shown 60 as applied to a double disk wheel in which the rear disk 43 extends in a substantially radial direction from the hub portion relieved by pockets 43^a. For use in the other forms of construction the front disk is 65 provided with the step or shoulder 44 which

cooperates with the shim 45 as hereinbefore described.

Fig. 7, corresponding to Fig. 7 of the parent application, illustrates a wheel comprising a single disk 46 provided with a stepped portion 47 and having associated therewith the rim-assembling shim 48, the functions performed thereby being substantially the same as described with reference to the foregoing figures. 75

I claim:

1. In a wheel, the combination of a hub portion, a tire-carrying portion, a medial disk portion provided with a step adjacent its periphery, and a tire-retaining member 80 having a fulcrum bearing at its inner edge upon the step.

2. In a wheel, the combination of a hub portion, a tire-carrying portion, a medial disk portion having an annular bead adjacent its periphery, and an annular tire-retaining member having a foot step fulcrum bearing upon the bead. 85

3. In a wheel, the combination with a hub, a tire and a tire-retaining member, of 90 a sheet steel disk having a peripheral step forming a fulcrum seating of the tire-retaining member, said disk being then reversely bent to form a felly.

4. In a wheel, the combination with a 95 hub, a tire and tire-retaining member, of a single sheet steel disk having a medial portion with a peripheral step forming a fulcrum seating of the tire-retaining member, said disk member being then reversely bent 100 to form a felly.

5. A disk wheel comprising a body portion and a peripheral tire-carrying portion, the body portion of the disk forwardly beaded a slight distance inwardly from its 105 periphery to form a fulcrum bearing for rim-positioning means, that portion of the disk between the bead and tire-carrying portion being substantially parallel to the plane of the wheel to accommodate a rim-positioning shim and to simulate the side 110 face of a felly.

6. A disk wheel comprising a body portion and a peripheral tire-carrying portion, the body portion of the disk forwardly 115 beaded a slight distance inwardly from its periphery, that portion of the disk between the bead and tire-carrying portion being substantially parallel to the plane of the wheel to simulate the side face of a felly, 120 and a tire-retaining member having a fulcrum bearing upon the disk outwardly of the bead.

7. A disk wheel comprising a body portion and a peripheral tire-carrying portion, the body portion of the disk forwardly beaded a slight distance inwardly from its periphery, that portion of the disk between the bead and tire-carrying portion being substantially parallel to the plane of 130

the wheel to accommodate a rim-positioning shim and to simulate the side face of a felly, the shim and disk presenting a substantially flush surface.

- 5 8. In a wheel, the combination of a hub portion, a medial disk portion, and an overhanging felly portion adapted to receive a demountable rim, the medial disk portion having an annular bead adjacent its 10 periphery, and an annular rim-retaining and supporting shim fulcrumed at its inner edge upon the bead, and bolts engag-

ing the shim and the disk outwardly of the bead for rocking the shim, whereby oppositely directed reaction is set up and maintained between the rim and that portion of the disk inwardly of the bead. 15

In witness whereof I have hereunto signed my name in the presence of two subscribing witnesses.

GEORGE H. FORSYTH.
